DESIGN FOR A DISPLAY STAND OR SIMILAR ARTICLE FOR JEWELRY AND THE LIKE

Morris Salinger, Brooklyn, N. Y.

Application September 13, 1944, Serial No. 115,293

Term of patent 14 years

(Cl. D80—9)

To all whom it may concern:

Be it known that I, Morris Salinger, a citizen of the United States, residing at Brooklyn, in the county of Kings and State of New York, have invented a new, original, and ornamental Design for a Display Stand or Similar Article for Jewelry and the like, of which the following is a specification, reference being had to the accompanying drawing, forming part thereof.

I claim:

The ornamental design for a display stand or similar article for jewelry and the like, substantially as shown.

MORRIS SALINGER.
